UNITED STATES PATENT OFFICE.

JOHN P. BALL, OF CHICAGO, ILLINOIS.

SAFETY APPLIANCE FOR AEROPLANES.

1,369,158.

Specification of Letters Patent. Patented Feb. 22, 1921.

Application filed June 7, 1920. Serial No. 387,261.

To all whom it may concern:

Be it known that I, JOHN P. BALL, a citizen of the United States, residing in the city of Chicago, county of Cook, State of Illinois, United States of America, have invented a new and useful Improvement in Safety Appliances for Aeroplanes, of which the following is a specification.

This invention relates to devices for application of an emergency brake for changing the center of gravity of an aeroplane in case of engine trouble or wreckage of any part of the machine.

Heretofore it has been common to use an independent parachute in case of an accident to an aeroplane, in which the aviator seizes the parachute and abandons the aeroplane.

My invention provides improvements especially applicable to safety devices of this general character and in its preferred form it utilizes two main rib members supporting the body of the machine and independent of the engine and operator's chair, two hinged rib members supporting the engine and operator's chair and hinged to the main body ribs at approximately the center of gravity of the body frame of the machine, a safety brake and hook holding the hinged rib member in a direct and parallel position to the body rib members while locked, and when released allows the engine to be lowered in a downward or right angular position to the body ribs.

My invention also includes an operator's chair independently mounted on a horizontal axle and supported in suitable bearings on the hinged engine-ribs, and is free to move in the bearings and being sufficiently balanced so as to maintain a direct or upright position while the hinged ribs are being lowered.

My invention also includes guy lines for supporting the planes in a balanced position and in the form of a parachute while the engine is in a downward or right angular location, means for securing the hinged engine-ribs to the main body ribs and means for tripping the hooked lever and thereby lowering the engine and operator's chair into a downward or rectangular location and thereby transforming the whole machine into the assumed form of a parachute, also a safety lock to secure the direct position of the hinged engine-ribs longitudinally with the main body ribs.

My invention also includes means for adjusting the guy lines and the lowering mechanism, thereby governing the horizontal position of the planes and balancing of the machine while in an emergency, and various features of improvements in construction arrangements and details all of which will be hereinafter more fully described.

My invention also includes a set of standard ribs, vertically located at approximately the center portion of the machine, the lower ends being supported by the main body ribs and the upper ends provided with pulleys engaging with an endless belt whereby the operator's chair and engine may be raised above the planes of the machine.

In the accompanying drawings which show certain adaptations of my invention, Figure 1 is a longitudinal view showing the engine and operator's chair in a direct position. Fig. 2 is also a longitudinal view and showing the engine and the operator's chair in an emergency or downward position or in a parachutal form. Fig. 3 is a vertical longitudinal section showing the details of the rib members, the tripping device, and the lowering mechanism. Fig. 4 is a horizontal longitudinal section showing the details of the body ribs.

Referring to the drawings A indicates the main body rib members, B the hinged engine-rib members, C the central hinge, D the tripping lever and hook, E the safety lock, F the axial center pin supporting the hinge joint, G the endless belt for lowering the engine-ribs and governing the location of the center of gravity of the machine, H the central engine pin to which the endless belt is secured, J the set of pulleys over which the endless belt passes, K the brake lever bearing on the forward pulley and controlling the lowering of the engine-ribs, L indicates the operator's chair supported on the axle M which in turn is supported in the bearings N on the hinged rib member. In Figs. 3 and 4 the standard ribs O are provided with a pulley P at the upper end thereof, Q represents the endless belt passing over the pulleys P and R, by which the hinged rib may be raised above the plane, Z represents the mechanism whereby the operator may raise or lower the hinged set of ribs.

Referring to Figs. 1 to 4, I will now describe in detail the preferred form of my invention in the adaptation herein illustrated.

There are two main body ribs A, the basic

support of the machine parts; these main ribs are situated longitudinally with the body of the machine and are applicable to any size or shape of aeroplane and constructed of any suitable material which will give strength to support the various parts of the machine, the main ribs A are braced to each other in any suitable manner, such as A frame bracing. These may be of the usual or suitable construction and arrangement capable of giving the required strength to the body support. There are two hinged ribs, B, for engine support and they consist of any suitable material of sufficient strength to carry the designed parts, and while in a direct position of the engine they are located parallel to and below the main rib members and are hinged thereto at about the center of the machine by means of eye bars and a main pin as shown at F in Fig. 3. The pin F is fixed to the two main rib members by means of clamps C. The eye bars that form the hinged ribs are free to rotate on the pin F and are held in place laterally by means of the nut heads d.

The engine and engine frame are supported by the hinged rib B by means of suitable clamps e, and while in a direct position the engine and engine frame together with the hinged rib are supported by the main rib member by means of the hook and lever D and the safety lock E while in a locked position. By releasing the hook f and the safety lock E the engine and engine frame is swung into the downward position as in Fig. 2.

The guy lines G are supported at the central pin H and at the several points of the winged planes suspend the whole frame in an approximately horizontal position.

In order to prevent the machine from dropping abruptly into a downward position, the main rib frame is provided with a set of pulleys J at the ends of the rib frame and an endless belt G fastened to the engine at H travels over the pulleys. The relative position of the engine ribs to the position of the body ribs may be regulated by means of endless belt passing over the operating pulley at Z, whereby the body ribs may be held in an inclinal or an anticlined position. The engine is lowered into a downward position by means of a brake lever, K, bearing on the forward pulley. The operator's chair is supported independently on the hinged rib member by means of the axle M and the bearings N, the chair member being free to rotate in the bearings and being suitably weighted so as to maintain an upright position regardless of the position of the hinged rib member.

The standard ribs O are constructed of suitable size and material so as to act as a mast for raising the engine ribs. The standard ribs are bolted at the lower end to the main set of body ribs at the approximate

center of the machine, the upper end is provided with a set of pulleys P on a cross arm between the standard ribs. An endless belt, Q, passes over the pulleys P and the pulleys at R and is fastened to the engine 70 ribs whereby the engine may be raised.

What I claim is:

1. In aeroplanes and devices of a similar character, a safety appliance of the class described, the combination of a set of main 75 ribs located longitudinally with the machine, a supplementary set of ribs hinged at one end to the approximately central point longitudinally of said main set of ribs, an engine and operator's chair on the outer end 80 of said supplementary ribs, lugs on said engine frame and hooked levers engaged therewith and means for moving said engine frame from a position in line with said main rib to a position below the hinged end of the 85 supplementary ribs.

2. In aeroplanes and devices of a similar character, the combination of a set of main ribs located longitudinally with the machine, and a set of supplemental ribs hinged 90 at one end to the approximately central point longitudinally of said main set of ribs, an engine and an operator's chair independently located on the outer end of said supplemental ribs and means for swinging 95 said supplemental ribs together with operator's chair and engine from a position in line with said body ribs to a position below the center of gravity of said machines whereby the center of gravity of said machines is lowered.

3. In aeroplanes and devices of a similar character, the combination of a set of main body ribs located longitudinally with the machine and a set of supplemental ribs 105 hinged at one end to the said main body ribs, said hinged point being located at the approximate center of gravity of body frame, a swinging operator's chair, an engine and engine frame located at the outer 110 end of said supplemental set of ribs, means for moving said swinging chair and said engine and engine frame from a position in line with said main body ribs to a position below the hinged inner end of the supplemental ribs.

4. In aeroplanes and devices of a similar character, the combination of a set of main body ribs located longitudinally with the machine, and a set of supplemental engine 120 ribs hinged at one end to the approximately central point loigitudinally of said main body ribs, means for swinging said engine ribs from a direct position in line with said body ribs to a tripped position below the 125 center of gravity of said machine, an operator's chair suspended in a swinging position axially from said engine ribs, lugs on said body ribs and hooked levers engaged therewith, means for lowering said engine 130

frame and operator's chair from a position in line with said body ribs to a position below the hinged inner end of the supplemental engine ribs, means for regulating the 5 relative position of the said supplemental engine ribs with the said main body ribs, whereby the position of the planes are either inclined or antinclined.

5. In aeroplanes and devices of a similar 10 character, a safety appliance of the class described, the combination of a set of main body ribs located longitudinally with the machine, a supplementary set of ribs hinged at one end to the approximately central 15 point longitudinally of said main body ribs,

an engine and an operator's chair on the outer end of said supplementary ribs, a set of standard ribs fixed at the lower end to the approximately central point of said body ribs and perpendicular thereto, an endless 20 belt engaging with a plurality of pulleys located at the upper end of said standard ribs and connected to said engine ribs whereby said engine ribs may be raised to a position above said machine.
